VENETIAN BLIND SLAT

John J. Gregory, Akron, Ohio

Application February 6, 1948, Serial No. 6,750

7 Claims. (Cl. 160—173)

1

This invention relates to an improved Venetian slat of the type having cord slots having an end opening through one edge thereof, with removable means for closing the open ends of the slots, the primary object of the invention being to provide an improved arrangement of this character which makes easier and quicker and simpler the removal of individual slats for cleaning or other purposes.

Another important object of the invention is the provision of a Venetian blind slat arrangement of the above indicated character involving readily removable clips for closing the open ends of the cord slots, which when in place securely maintain their positions, and which in the cases of both individuals and manufacturers are time and labor saving from the standpoint of assembling the slats in a Venetian blind because of the ease and celerity with which the clips may be installed.

Another important object of the invention is to provide an arrangement of the above indicated character wherein the clips are made of extremely light weight but adequately strong material such as plastic material or light weight metals, such as aluminum or magnesium, so that the clips cannot unduly weight the blind slats or unbalance them, such materials and the construction of the clips also affording possibilities of unobtrusive appearance or ornamental appearance as may be desired.

Other important objects and advantageous features of the invention will be apparent from the following description and the accompanying drawings, wherein for present purposes of illustration only, a specific embodiment of the invention is set forth in detail.

In the drawings:

Figure 1 is a perspective view of the underside of the clip, on an enlarged scale.

Figure 2 is a fragmentary top plan view, on a reduced scale, showing the clip installed at the open end of one of the slots of a Venetian blind slat.

Figure 3 is a bottom plan view of Figure 2.

Figure 4 is a left hand edge elevation of Figure 3, and,

Figure 5 is a section taken on the line 5—5 of Figure 3.

Referring in detail to the drawings, the numeral 6 generally designates a metal slat of a Venetian blind formed with a transverse cord accommodating slot 7 opening through one edge of the slat, as indicated at 8. Instead of the slot 7 being of the same width throughout its length,

2

approximately half of the length thereof inwardly from the open end is of narrower width, presenting edges 9, 9 which are laterally inset from the edges 10, 10 of the normal width cord receiving portion of the slot 7.

In addition to the novel reshaping of the slot 7, the slat edge 11 through which the slot 7 opens is formed at each side of the opening 8 with short narrow slots 12, 12, running parallel to the main slot 7 and spaced from opposite sides thereof at distances approximately the width of the slots 12, 12, and defining tabs 13, 13.

The clip for association with the main and supplementary slots, generally designated 14, comprises a flat generally segmental body 15 of lightweight plastic or other suitable material having the upper corners of the converging edges 16, 16 rounded as indicated at 17 for smooth manual contact and appearance, and having the upper corner of the narrow end 18 similarly rounded, as indicated at 19, this narrow end being curved inwardly between its terminal ends at 20 to provide a smooth rounded contact area for the blind cord 21 in the slot 7.

The underside of the body 15 is substantially plane and formed on its longitudinal middle with an elongated flat portion 24 which extends from the wider end 25 to the smaller end 18 of the body. The portion 24 has parallel side edges 26, 26 whose lower corners are rounded, as indicated at 27 and whose inner end is curved and rounded at 28 to match the curvature of and form a continuation of the curved area 19, so that the clip can engage the blind cord 21 without appreciable friction or chafing.

The side edges 26, 26 are undercut to define grooves 29, 29 which open through the wider end of the body 15 but terminate at a point close to the smaller end of the body 15 to define curved shoulders 30 to mate with similarly curved edge portions 31, 31 at the outer end of the cord accommodating portion of the slot 7.

The grooves 29, 29 slidably accommodate the edges 9, 9 of the narrower portion of the cord slot 7, which are also the inner edges of the tabs 13, 13, while the outer edges of these tabs are slidably engaged by the ungrooved laterally inward sides of the locking lugs 33, 33, which are parallelly spaced from the sides of the portion 24 at such distances that the inward edges of the tabs are frictionally and slidably confined in the grooves 29, 29. The lugs 23, 23, which are similar but reversed in position, are approximately the length of the supplementary locking slots 12, 12 but slightly wider than these slots and have

rounded upper surfaces 34. The laterally outward sides of the lugs are undercut to define grooves 35, 35 which frictionally and slidably receive the corresponding edges of the slots 12, 12. The grooves 29, 29 and 35, 35 are of a width to frictionally and slidably engage the upper and lower surfaces of the blind slat 6.

In installing the clip 14, the clip is held in approximately the same plane as the blind slat 6 and with the smaller end 18 toward the blind slat, the body portion 24 and the lugs 33, 33 are simultaneously inserted in the open ends of the main slot 7 and locking slots 12, 12 and the clip pushed toward the opposite edge of the blind slat until the wider end 25 of the clip is substantially flush with the edge 11 of the blind slat. The flexibility of the blind slat material is such that the sides of the narrow portion of the slot 7 are deflected and spread by the movement of the clip across the slat, so that the rounded shoulders 30 can get behind and conformably engage the shoulder portions 31, 31 at the inner end of the narrow blind slat portion, so thereafter force, exerted either by the weight of the clip, by the pressure of the cord 21 against the clip, or by ordinary handling of the Venetian blind will not dislodge the clip, and a manual pull upon the clip in an outward or retracting direction will be required to displace and remove the clip from the main and supplementary locking slots.

What is claimed is:

1. A Venetian blind slat formed with a transverse cord accommodating slot opening through one edge thereof, and a clip comprising a plate-like body lying along one side of said slat and bridging said cord slot, said body having a relatively narrow laterally-projecting portion positioned in said cord slot, said portion being formed in its edges with grooves slidably and frictionally receiving the related edges of said cord slot whereby said clip is removably secured to said slat and the open end of said cord slot is closed to retain a cord therein, said blind slat being further formed with relatively narrow and short supplementary locking slots spaced from opposite sides of said cord slot and opening through said one edge of the slat whereby tabs are defined at opposite sides of said cord slot, and said body having relatively narrow and short locking lugs projecting laterally from said body at opposite sides of said laterally-projecting portion positioned in said locking slots.

2. A Venetian blind slat formed with a transverse cord accommodating slot opening through one edge thereof, and a clip comprising a plate-like body lying along one side of said slat and bridging said cord slot, said body having a relatively narrow laterally-projecting portion positioned in said cord slot, said portion being formed in its edges with grooves slidably and frictionally receiving the related edges of said cord slot whereby said clip is removably secured to said slat and the open end of said cord slot is closed to retain a cord therein, said blind slat being further formed with relatively narrow and short supplementary locking slots spaced from opposite sides of said cord slot and opening through said one edge of the slat whereby tabs are defined at opposite sides of said cord slot, and said body having relatively narrow and short locking lugs projecting laterally from said body at opposite sides of said laterally-projecting portion positioned in said locking slots laterally outward sides of said locking lugs being formed with grooves

receiving the laterally outward edges of said locking slots are engaged.

3. A Venetian blind slat formed with a transversely-extending cord slot opening through one edge thereof, and a clip for closing the open end of the cord slot, said clip comprising a plate-like body engaging one side of the blind slat in bridging relation to said cord slot, the side of said body engaging the blind slat having a projection positioned in and closing the outer end of the cord slot, said projection being formed in its opposite edges with grooves receiving related edges of the cord slot.

4. A Venetian blind slat formed with a cord slot extending across the slat and opening through an edge thereof, and a clip for closing the open end of the cord slot, said clip comprising a plate-like body lying along and engaging one side of the blind slat and extending across the cord slot, the side of said body engaging the blind slat having a projection elongated in the direction of the cord slot and positioned in the open end of the cord slot, said projection being formed in opposite sides with longitudinal slots receiving the related edges of the cord slot, the said one edge of said blind slat being formed with locking slots spaced at opposite sides of said cord slot, and said plate-like body having locking lugs on the side thereof engaging the blind slat, said locking lugs being spaced from the sides of said projection and being frictionally engaged in said locking slots.

5. A Venetian blind slat formed with a cord slot extending across the slat and opening through an edge thereof, and a clip for closing the open end of the cord slot, said clip comprising a plate-like body lying along and engaging one side of the blind slat and extending across the cord slot, the side of said body engaging the blind slat having a projection elongated in the direction of the cord slot and positioned in the open end of the cord slot, said projection being formed in opposite sides with longitudinal slots receiving the related edges of the cord slot, the said one edge of said blind slat being formed with locking slots spaced at opposite sides of said cord slot, and said plate-like body having locking lugs on the side thereof engaging the blind slat, said locking lugs being spaced from the sides of said projection and being frictionally engaged in said locking slots, said locking slots opening through the same edge of said slat as said cord slot, the laterally outward sides of said locking lugs being formed with grooves receiving the related edges of said locking slots.

6. A Venetian blind slat formed with a cord slot extending across the slat and opening through an edge thereof, and a clip for closing the open end of the cord slot, said clip comprising a plate-like body lying along and engaging one side of the blind slat and extending across the cord slot, the side of said body engaging the blind slat having a projection elongated in the direction of the cord slot and positioned in the open end of the cord slot, said projection being formed in opposite sides with longitudinal slots receiving the related edges of the cord slot, the said one edge of said blind slat being formed with locking slots spaced at opposite sides of said cord slot, and said plate-like body having locking lugs on the side thereof engaging the blind slat, said locking lugs being spaced from the sides of said projection and being frictionally engaged in said locking slots, said locking slots opening through the same edge of said slat as said cord slot, the laterally outward sides of said locking lugs being

formed with grooves receiving the related edges of said locking slots, the slots of said projection and the slots of said locking lugs being of sufficient depth to define portions frictionally engaging the opposite sides of said blind slat in the region of said cord slot and locking slots.

7. A Venetian blind slat formed with a transversely-extending cord slot opening through one edge thereof, and a clip for closing the open end of the cord slot, said clip comprising a plate-like body engaging one side of the blind slat in bridging relation to said cord slot, the side of said body engaging the blind slat having a projection positioned in and closing the outer end of the cord slot, said projection being formed in its opposite edges with grooves receiving related edges of the cord slot, said cord slot having laterally-inwardly-extending portions of the edges thereof adjacent to the open end of said cord slot defining a

narrow slot portion and shoulders at the inward ends of said edge portions, said projection having laterally outwardly-extending stops on the opposite edges thereof positioned at the inward ends of the slots in said opposite edges, said stops being arranged to engage said shoulders whereby outward movement of said clip relative to said blind slat from closing relation to the open end of the cord slot is resisted.
